UNITED STATES PATENT OFFICE.

LOUIS S. BURBANK, OF HOPEDALE, MASSACHUSETTS, ASSIGNOR, BY MESNE ASSIGNMENTS, TO DRAFER CORPORATION, OF HOPEDALE, MASSACHUSETTS, A CORPORATION OF MAINE.

WARP STOP-MOTION FOR LOOMS.

1,240,666.

Specification of Letters Patent. Patented Sept. 18, 1917.

Application filed December 26, 1914. Serial No. 879,005.

To all whom it may concern:

Be it known that I, LOUIS S. BURBANK, a citizen of the United States, residing at Hopedale, county of Worcester, State of Massachusetts, have invented an Improvement in Warp Stop-Motions for Looms, of which the following description, in connection with the accompanying drawing, is a specification, like characters on the drawing 10 representing like parts.

This invention relates to warp stop motions for looms of the general type and in its preferred form to that type of warp stop motion wherein controlling detectors are suspended from the warps and normally held thereby out of the path of a vibrating feeler, release of a detector by failure of the warp restraining vibration of the feeler and wherein upon such restraining movement is 20 transmitted to a pivoted dog mounted on the loom frame to move the dog into the path of a bunter carried by the lay and thereby to effect a change in the operation of the loom, such as the stopping of the 25 loom through the usual knock-off lever.

The invention in one of its broad features involves a novel means of transmitting movement from the warp failure detecting means to the loom change effecting means and the 30 invention in its broader aspects is therefore not limited to the particular kind of warp failure detecting means, nor the particular kind of loom change effecting means between which the movement is transmitted.

Another object of the invention is to provide a connecting means for the transmission of movement from the warp failure detecting means to the loom change effecting means of such a character that either of the 35 means so connected may be adjusted or re-positioned without requiring an adjustment or re-positioning of the connecting means.

Another feature of the invention resides in the provision of a flexible connector extending between the said means and acting by the transmission of thrust therethrough to cause the actuation of the loom change effecting means upon detection of a warp failure. The invention also presents connecting means of few parts, of simple and easy construction, eliminates the necessity for springs in constant action in the warp failure detecting means, renders the adjustment of all the parts simple and easy, relieves the working parts of strain, readily

enables the feeler to be jiggled to ascertain the location of the dropped detector and secures many other advantages.

The objects and nature of the invention will more fully appear from the accompanying description and drawings and will be defined in the appended claims.

The drawings show so much of one type of automatic filling replenishing loom as is necessary to a disclosure of the present invention.

In the drawings,

Figure 1 is a left hand side elevation of a sufficient portion of the loom with a preferred embodiment of the present invention applied thereto, the shafts being shown in section;

Fig. 2 is a detail in vertical section showing the construction and mounting of the dog and adjacent parts;

Fig. 3 is a front elevation of a portion of the loom showing the preferred form of parts embodying the invention in place;

Fig. 4 is a detail partially in horizontal cross section of the parts connected to the 80 feeler rock shaft and taken on the line x-x, Fig. 5;

Fig. 5 is an end view partially in cross section of the construction shown in Fig. 4.

This invention is illustrated in its preferred form in connection with a type of loom provided with warp failure detecting means and loom change effecting means such in general as shown, for example, in the

to Ambler No. 885,130 granted April 21, 1908. The loom change effecting means is herein shown as a loom stopping means and specifically as a means for knocking off the shipper by which the loom is stopped. The particular construction of the loom and the various mechanisms with which the present invention is designed to co-operate is not involved in the present invention and may take various forms.

Referring to the particular construction illustrated the lay 1 has secured thereto and depending therefrom the usual bunter 2, the effective portion of which points to the rear of the loom. The usual shipper 3 by which the belt is shifted from the fast to the loose pulley to stop the loom is moved to stopping position by a knock-off lever 4 pivoted at 5 to the loom side 6. In the construction illustrated this knock-off lever 4 is by its shape weighted so as normally to

swing to running position as shown in Fig. 1 without requiring a spring to throw it to such position.

A link is pivotally connected at 7 to an upwardly extending arm of the knock-off lever and at its other end by a pivot 8 to a dog 9. This link is made in two parts 10 and 11 adjustably connected together by the set screws 12. If now the dog 9 be swung 10 upwardly on its pivot into the path of the bunter 2 this bunter on the rearward movement of the lay will catch on the dog and through the medium of the link throw the knock-off lever to move the shipper and 15 stop the loom.

In the construction of this invention the pivot 8 connecting the link and the dog is carried at the upper end of a link connection 13, the lower end of which is pivoted 20 at 14 to some portion of the loom frame such as the bracket 15 herein shown as secured to the loom side. This connection as will be explained later causes the dog as 25 it is moved rearwardly also to be slightly bodily moved upwardly.

The warp failure detecting means herein illustrated in connection with the present invention is in its main features of a well known and familiar type. It comprises a 30 number of detectors 16 preferably arranged in two series transversely of the loom slotted to pass over the detector supporting bar 17 and each detector suspended from a warp thread. A vibrating feeler shown as a horizontal plate 18 supported on the arms 19 extending from the feeler rock shaft 20 is constantly vibrated beneath the detector supporting bars. Upon the failure of a 35 detector drops bringing its end below the plane of the feeler plate 18 and consequently vibration of the feeler is restrained. This restraint of movement of the vibrating feeler is made use of in this type of mechanism to effect the movement of the dog 9 40 into the path of the bunter 2.

In the construction herein illustrated in connection with the present invention the feeler arms 19 are rigidly secured at 21 to the feeler rock shaft 20. An abutment 22 is also rigidly secured as by the set screw 23 to the rock shaft 20; a collar 24 is rigidly secured by the set screw 25 to the rock shaft between the abutment and one of the feeler 50 supporting arms 19. A sleeve 26 is loosely mounted on the rock shaft 20 between the abutment 22 and the collar 24 so as to be capable of rotary and sliding movement on the rock shaft. This sleeve and the adjacent abutment are formed with co-operating 55 cam surfaces as shown for example in Fig. 4. A helical spring 27 extends between the collar 24 and sleeve 26 and acts to maintain the cam surfaces of the sleeve and abutment 60 in contact.

The sleeve 26 is provided with a forwardly projecting arm 28 and this arm is vibrated by a connection to the cam shaft 29. This vibrating connection is itself of 70 novel form. It comprises a link 29* pivoted to the arm 28 offset at 30 to clear the main shaft 31 and the parts carried by it, and is adjustably connected at 32 at its lower end to a yoke 33 straddling the cam shaft 29. This yoke has pivoted at either 75 side a crescent shaped cam follower 34. The operating cam 35 is a face cam secured to the cam shaft 29 at either side of the yoke 33 as particular conditions require, and this reversible construction of the cam and follower is very desirable. The cam 35 is provided on its face with the double concentric switching groove 36 of the general form 80 illustrated in Fig. 1. This preferred construction gives a comparatively slow vibration to the rock shaft 20 and consequently 85 to the feeler.

The present invention is more particularly concerned with the means for transmitting the indication of warp failure to effect the 90 operation of the loom change effecting means such as the knock-off motion, and in the particular form illustrated to a mechanism of this type comprising the pivoted dog which is moved into the path of a 95 bunter on the lay.

It is very desirable in loom mechanisms 100 of this type to be able to adjust and re-position the elements of the warp protecting means and the elements of the loom stopping means or loom change effecting means such as the dog, bunter and connected parts and make these adjustments and re-positionings independently of the other. This result is readily effected by the present invention.

The main feature of this invention is the provision of a flexible connector by means of which a thrusting movement is transmitted from the warp failure detecting means 110 to the loom change effecting means. This is secured by a flexible connector having a plurality of parts, preferably two, which are substantially conterminous and juxtaposed, and which are longitudinally and relatively 115 movable and by making use of this relative movement.

In the preferred form illustrated this flexible connector comprises a flexible sheath 120 herein shown as a long wire helix of small diameter and a flexible core of wire fitting inside the sheath. The relative movement of these two parts of the flexible connector is provided for by securing the sheath at its ends against longitudinal movement while 125 permitting longitudinal movement of the internal core.

The flexible sheath 37 is herein shown as secured against longitudinal movement at one end adjacent the loom change effecting 130

means in the bracket 15 and at its other end in a socket in the arm 38 rigid with the rear arm 19. In each instance a split steel sleeve or bushing 39 surrounds the sheath in the 5 socket and is held in place and caused to clamp the sheath by a set screw 40. Between these points it may be carried wherever desired and is shown as passing through the loom side. It hangs loosely and thus the 10 distance between its rigidly supported ends may be varied as required to allow of any independent re-adjustment of the mechanisms of the loom.

The flexible core or wire 41 adjacent the 15 dog 9 preferably contacts with a pin or plunger 42 sliding in a socket in the bracket 15 and this pin is so positioned as just to contact with the dog 9 when the dog is in its normal or ineffective position.

20 Thrust may be transmitted to the core 41 at the opposite end upon the restraint of the vibrating feeler in any suitable manner. As a preferred construction there is herein shown a rod 43 having one end entering 25 the sleeve or bushing 39 in the arm 38 and abutting the end of the core 41 and having its other end seated in a socket in the sleeve 26. Owing to the fact that the sleeve 26 and arm 28 have a relative rotary movement 30 the rod 43 at each end has a universal connection which may be of the types illustrated in Fig. 4.

When thrust is imparted to the core 41 that thrust will be transmitted to the pin 42 35 causing the elevation of the dog 9. The core 41 is returned in the opposite direction by the weight of the parts including the dog 9 and also by the action of a helical spring 44 seated in a socket in the rearward 40 end of the link part 11 and abutting against the dog 9.

It will also be noted by reason of the link construction 13 already described that when a thrust has been imparted to the core 41 45 causing the pin 42 to raise the dog to active position into the path of the bunter 2 and the bunter comes in contact with the dog carrying it rearwardly that the dog will by reason of the link connection be bodily 50 raised slightly thus clearing the pin 42 and the stop on the bracket against which the dog normally rests, and leaving a slight space between the pin and the dog. This leaves lost motion so that the operative taking 55 hold of the usual handle 45 connected with an arm 46 on the feeler rock shaft can jiggle the feeler and ascertain the position of the detector which has dropped.

The operation of the loom and the parts 60 involved in this invention in the preferred form illustrated will now be apparent. With the loom running the knock off lever 4 is in the position shown in Fig. 1, the dog 9 is in its lower or inactive position and 65 the cam 35 is slowly vibrating the feeler

rock shaft 20, and consequently the feeler 18 beneath the ends of the detectors 16 supported on the detector bars. If now a warp fails its corresponding detector drops into the path of the vibrating feeler 18 and 70 holds it and the connected rock shaft 20 against vibration. But as the action of the cam 35 continues the sleeve 26 loosely mounted on the shaft also continues vibration, and consequently is forced longitudinally 75 on the shaft against the tension of the spring 27 by the action of the cooperating cam surfaces on the sleeve and abutment 22. This causes the rod 43 to move longitudinally and transmit its movement to the core 80 41 of the flexible connector. This longitudinal movement is transmitted through the core and its pin 42 to the dog 9 elevating the dog against the action of the spring 44 into the path of the bunter 2. As the lay 85 beats back the bunter 2 strikes the dog 9 carrying back with it the dog, the link 11, 10 and swinging the knock-off lever 4 against the shipper to stop the loom.

Having fully described my invention, 90 what I claim as new and desire to secure by Letters Patent is:

1. A loom comprising loom change effecting means; a lay provided with a bunter; a dog connected with the loom change effecting means, mounted on the loom frame, movable into the path of the bunter, and acting when struck by the bunter to actuate the said loom change effecting means; warp failure detecting means; a flexible sheath 95 having its ends secured against longitudinal movement, one adjacent said dog and the other adjacent said detecting means; a flexible core located in, and longitudinally movable with respect to, and laterally supported 100 by, said sheath; and means operated by said detecting means upon detection of a warp failure to transmit a longitudinal thrust to said core and therefrom to said dog to move the dog into the path of the bunter and thus 105 effect the actuation of the loom change effecting means.

2. A loom comprising warp failure detecting means; loom change effecting means; a flexible connector extending between said 110 means and comprising two relatively and longitudinally movable substantially conterminous juxtaposed parts which act to prevent relative transverse movement; and means for operating by or through a longitudinal thrust of one of said connector parts the loom change effecting means upon a detecting action of the warp failure detecting means.

3. A loom comprising warp failure detecting means; loom change effecting means; a flexible connector comprising a sheath rigidly secured at its ends adjacent said respective means and extending between said means, and a core longitudinally movable 120 130

in said sheath and prevented from relative transverse movement thereby; and means for operating by a thrusting movement of said core the loom change effecting means 5 upon a detecting action of the warp failure detecting means.

4. A loom comprising loom change effecting means; a vibrating feeler; a flexible connector comprising two relatively and longitudinally movable substantially continuous juxtaposed parts which act to prevent relative transverse movement; a warp failure detecting means comprising a plurality of detectors each movable upon failure 10 of its corresponding warp into an abnormal position and when so moved acting to restrain vibration of the feeler; and means actuated upon the restraint of the feeler to transmit a longitudinal thrust to one of 15 said connector parts and thereby to cause the operation of the loom change effecting means.

5. A loom comprising loom change effecting means, a vibrating feeler; a flexible connector comprising a sheath having its ends secured adjacent said feeler and said loom change effecting means, and a core in 20 said sheath movable longitudinally thereof, and thereby prevented from transverse movement with respect thereto; a warp failure detecting means comprising a plurality of detectors each movable upon failure 25 of its corresponding warp into an abnormal position and when so moved acting to restrain vibration of the feeler; and means actuated upon the restraint of the feeler to transmit a longitudinal thrust to said core and therethrough to cause the operation of the loom change effecting means.

6. A loom comprising loom change effecting means; a rock shaft; a feeler secured to said rock shaft; a flexible connector extending from adjacent said feeler to adjacent said loom change effecting means and comprising a sheath having its ends secured 30 against longitudinal movement; and a core longitudinally movable in said sheath and thereby prevented from transverse movement with respect thereto; a sleeve slidably 35 and rotarily mounted on said rock shaft and an abutment rigidly mounted on said rock shaft, the said sleeve and abutment being provided with coöperating cam surfaces, and a spring for normally holding the sleeve 40 in engagement with the abutment; means for vibrating the sleeve and through it the abutment, rock shaft, and feeler; a connection between said sleeve and core whereby upon longitudinal movement of the sleeve a longitudinal thrust will be transmitted to 45 the core; a warp failure detecting means comprising a plurality of detectors each movable upon failure of its corresponding warp into an abnormal position and when 50 so moved acting to restrain vibration of the

feeler, rock shaft and abutment whereby through the action of the coöperating cam surfaces the sleeve will be moved against the action of the spring and a longitudinal thrust transmitted to the core to cause the 70 operation of the loom change effecting means.

7. A loom comprising warp failure detecting means; loom change effecting means; a flexible sheath having its ends secured 75 against longitudinal movement one adjacent said warp failure detecting means and the other adjacent said loom change effecting means, a flexible core located in and longitudinally movable with respect to said sheath and prevented thereby from transverse movement with respect thereto; and means operated by said detecting means upon detection of a warp failure to transmit a longitudinal thrust to said core and thereby to effect the actuation of the loom 80 change effecting means.

8. A loom comprising loom change effecting means; a rock shaft; a feeler secured to said rock shaft; a flexible connector extending from adjacent said feeler to adjacent said loom change effecting means and comprising a sheath having its ends secured against longitudinal movement, and a core longitudinally movable in said sheath; a sleeve slidably and rotarily mounted on said rock shaft and an abutment rigidly mounted on said rock shaft, the said sleeve and abutment being provided with coöperating cam surfaces, and a spring for normally holding the sleeve in engagement with the abutment; means for vibrating the sleeve and through it the abutment, rock shaft and feeler; a rod having a bearing at one end in 90 said sleeve and at the other end entering said sheath and abutting said core whereby upon longitudinal movement of the sleeve longitudinal movement will be transmitted through said rod to the core; and warp failure detecting means acting upon warp 95 failure to restrain vibration of the feeler rock shaft and abutment whereby through the action of the coöperating cam surfaces the sleeve will be moved against the action of the spring transmitting longitudinal 100 movement through the rod and core to cause the operation of the loom change effecting means.

9. A loom comprising loom change effecting means; a lay provided with a bunter; a dog connected with the loom change effecting means, pivoted on the loom frame, movable into the path of the bunter, and acting when struck by the bunter to actuate the said loom change effecting means; warp 120 failure detecting means; a flexible sheath having its ends secured against longitudinal movement; one adjacent said dog and the other adjacent said detecting means; a flexible core located in, and longitudinally mov- 125

able with respect to, said sheath and having a pin engaging said dog; and means operated by said detecting means upon detection of a warp failure to transmit longitudinal movement to said core and thereby to cause the pin to move the dog into the path of the bunter and thus effect the actuation of the loom change effecting means.

10. A loom comprising loom change effecting means; a lay provided with a bunter; a dog connected with the loom change effecting means, pivoted on the loom frame, movable into the path of the bunter, and acting when struck by the bunter to actuate the said loom change effecting means; warp failure detecting means; a flexible sheath having its ends secured against longitudinal movement, one adjacent said dog and the other adjacent said detecting means; a flexible core located in, and longitudinally movable with respect to, said sheath and having a pin engaging said dog; and means operated by said detecting means upon detection of a warp failure to transmit longitudinal movement to said core and thereby to cause the pin to move the dog into the path of the bunter and thus effect the actuation of the loom change effecting means; and a spring acting on said dog in opposition to the thrust of said core.

11. A loom comprising loom change effecting means; a lay provided with a bunter, a dog connected with the loom change effecting means, mounted on the loom frame, movable into the path of the bunter, and acting when struck by the bunter to actuate the said loom change effecting means; warp failure detecting means; a flexible connector extending between said dog and said warp failure detecting means and comprising two relatively and longitudinally movable substantially conterminous juxtaposed parts one of which acts to support the other throughout against transverse movement with re-

spect thereto; and means actuated by said detecting means upon detection of a warp failure for moving by or through a longitudinal thrust of the said transversely supported connector part the dog into the path of the bunter and thus effecting the actuation of the loom change effecting means.

12. A loom comprising loom change effecting means; a lay provided with a bunter; a dog connected with the loom change effecting means; a link connection between said dog and the loom frame whereby when the dog is moved into the path of the bunter it will be struck thereby to actuate the said loom change effecting means and will be bodily moved away from the point of pivotal connection of the link and loom frame; a vibrating feeler; a flexible connector comprising a sheath having its ends secured adjacent said feeler and said dog and a core in said sheath movable longitudinally thereof and having a pin and normally in contact with said dog; a warp failure detecting means comprising a plurality of detectors each movable upon failure of its corresponding warp into an abnormal position and when so moved acting to restrain vibration of the feeler; and means actuated upon the restraint of the feeler to move said core longitudinally and therethrough to move the dog into the path of the bunter; whereby when the dog is struck by the bunter the dog moves away from the pin of the core thus permitting jiggling of the vibrating feeler to ascertain the abnormally located detector.

In testimony whereof, I have signed my name to this specification, in the presence of two subscribing witnesses.

LOUIS S. BURBANK.
